UNITED STATES PATENT OFFICE.

ALBERT SCHULTZ, OF DAYTON, OHIO.

PULP-FEED REGULATOR.

943,165.

Specification of Letters Patent. Patented Dec. 14, 1909.

Application filed April 21, 1909. Serial No. 491,245.

To all whom it may concern:

Be it known that I, ALBERT SCHULTZ, a citizen of the United States, residing at Dayton, in the county of Montgomery and State 5 of Ohio, have invented certain new and useful Improvements in Pulp-Feed Regulators; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to new and useful improvements in regulators for feeding pulp to paper-making machines.

The invention is adapted for use in connection with the common type of pulp box 20 in which there are three compartments, an entering compartment connected to the supply pump, a discharge compartment connected with the paper-making machine, and an over-flow compartment connected with 25 the well from which the pulp is pumped. The pulp is supplied to the entering compartment from the aforesaid pump which is operated at the same speed for different weights of paper. It is therefore customary 30 to place a gate within the box to regulate the amount of flow to the discharge compartment and thence to the machine. The pump, however, does not always discharge evenly which results in a varied grade of paper.

35 The object therefore, of this invention is to regulate this gate automatically and thereby secure an even grade of paper.

Referring to the annexed drawings, Figure 1, is a top plan view of my invention. 40 Fig. 2, is a sectional view on the line *b b* of Fig. 1. Fig. 3, is a sectional view on the line *a a* of Fig. 1.

In the following description, similar reference characters indicate corresponding 45 parts.

The pulp receptacle or box 1 is divided into three compartments 4 5 and 6, by two division walls 2 and 3, compartment 6 is the entering compartment which is connected to 50 a supply pump (not shown) by a pipe 9, the pump as before stated, having a pipe connection with the pulp well. Compartment 4 is the discharge compartment from which the pulp flows to the paper-making machine 55 (not shown) through a pipe 7. The over-flow compartment 5 is provided with an out-

let 8 connecting with the pulp well (not shown) from which the pulp is previously pumped. The pulp, which is in solution, enters the compartment 6 and overflows the 60 wall 2. A gate 10 pivoted at 11 to the wall 2 diverts the flow into the compartments 4 and 5. When said gate is in a central position, the flow of pulp into the two compartments 4 and 5 will be equal, but if said gate 65 is placed to one side, the flow of pulp will be diverted to one or the other of said compartments 4 and 5, depending upon the position of said gate.

The gate 10 is provided with a sleeve or 70 telescopic connection 12 which engages a crank 13 on a rock shaft 14, the latter having bearings 17 and being provided with an extended arm 15 on the outer end of which is attached a float 16. The float 16 75 lies within the entering compartment 6 and rises and falls with the pulp solution in said compartment. It will therefore be seen that when the pulp in said compartment rises, the gate 10 will be drawn to the left, thus 80 increasing the flow of pulp into the compartment 5 and maintaining a steady flow in the compartment 4. When the float 16 falls the gate will be drawn to the right, but the amount of pulp passing to the compartment 4 will not increase as the head 85 also decreases in the entering compartment 6. The over-flow or upper edge of the wall 2 is preferably placed at an angle, as the stroke of the gate 10 is thereby made more 90 effective. The angles of the upper end of the wall 2 converge downwardly to the center of the said wall, at which point, the gate 10 is pivoted. When it is desired to increase the constant flow of pulp to the paper-mak- 95 ing machine, in order to secure a heavier quality of paper, the telescopic connection 12 may be lengthened; if it is desired to secure a lighter quality of paper, said connection may be accordingly shortened, as will be 100 readily understood.

In do not wish to limit myself to the particular type of gate shown and described, as it will be readily seen that a sliding gate may be utilized for the purpose of regulating the feed of pulp.

I claim:

1. In a device of the type specified, a pulp box having entering, discharge, and over-flow compartments, the construction of said 110 box being such as to allow the pulp to flow from the entering compartment into the

discharge compartment and the overflow compartment, a float in the entering compartment, and a gate pivoted below its center controlled by said float, said gate 5 controlling the flow of pulp from the entering compartment.

2. In a device of the type specified, a pulp box having an entering compartment, a discharge compartment, and an over-flow compartment, said box being constructed to 10 allow the pulp to flow from the entering compartment into the discharge and over-flow compartments, a float within the entering compartment, an upright gate pivoted at its lower end to the wall which 15 divides the entering compartment from the discharge and over-flow compartments, and a connection between said gate and said float whereby the gate is rocked to regulate 20 the flow of pulp to the discharge or over-flow compartment.

3. In a device of the type specified, a pulp box having an entering compartment, and discharge and over-flow compartments, 25 the wall separating the entering from the discharge and over-flow compartments hav-

ing its upper edge tapered downwardly and converging at the center of said wall, a gate pivoted to the center of said wall, a float in the entering compartment, and a connection 30 between said float and said gate, whereby the gate is automatically operated to regulate the feed of pulp from the entering compartment to the discharge or over-flow compartments.

4. In a pulp regulator for paper-making machines, a pulp box having a main partition the upper edge of which is substantially V-shaped, a swinging gate pivoted to said partition and coöperating with the V-shaped edge thereof in regulating the flow of pulp, 40 a float, and connections between said float and the gate for varying the opening between the upper edge of the partition and the gate.

In testimony whereof I affix my signature, in presence of two witnesses.

ALBERT SCHULTZ.
